P. C. SNOW

CHECK NOTCHING DEVICE

Filed Feb. 21. 1922

Inventor
Philip C. Snow

James L. Morris.

Attorney

UNITED STATES PATENT OFFICE.

PHILIP C. SNOW, OF SWARTHMORE, PENNSYLVANIA, ASSIGNOR TO GLOBE TICKET COMPANY, OF PHILADELPHIA, PENNSYLVANIA, A CORPORATION OF PENNSYLVANIA.

CHECK-NOTCHING DEVICE.

Application filed February 21, 1922. Serial No. 538,372.

To all whom it may concern:

Be it known that I, PHILIP C. Snow, a citizen of the United States, residing at Swarthmore, in the county of Delaware and 5 State of Pennsylvania, have invented new and useful Improvements in Check-Notching Devices, of which the following is a specification.

The present invention relates to improvements in check holding and notching devices and more particularly to those of the general class adapted to hold a pad or pack of restaurant or similar checks and provided with means for notching and thereby 10 marking checks detached from the pack, thus indicating on each check the amount of a purchase or the amount the purchaser is to pay the cashier.

The primary object of the invention is 20 to provide simplified and improved means for notching the checks whereby the check to be notched may be easily and quickly placed in proper position for notching, the check so placed can be quickly and firmly gripped by a notching member, and moreover, the notching of the check can be effected quickly and cleanly by a simple manipulation of the check while it is firmly held by the notching member.

To these and other ends, the invention 30 consists in certain improvements and combinations and arrangements of parts, all as will be hereinafter more fully described, the features of novelty being pointed out particularly in the claims at the end of the specification.

In the accompanying drawing:—

Figure 1 is a perspective view of a check holding and notching device constructed in 40 accordance with the present invention, this figure showing the manner of placing a detached check in position for notching;

Figure 2 is a view of the back or rear side of the device as shown in Figure 1;

Figure 3 is an edge view partly in section of the device as shown in Figures 1 and 2; and

Figures 4 and 5 are plan and edge views respectively of the notching member.

Similar parts are designated by the same reference characters in the several views.

The present invention is applicable generally to ticket or check holding and notching devices of the general class in which 55 the pad or pack of checks, designated X,

is held on the forward side of a base plate or support 1 by a holder 2 which may be of any suitable construction and usually engages the stub portion x of the pad. The checks are usually sub-divided along one or 60 more marginal edges and provided with amount indicating numerals and other characters to designate the matter to be indicated or marked on the check. The arrangement of the sub-divisions and the indicating numerals or characters may be varied to meet the desires of the user.

The device for marking the detached checks is preferably of the type which notches a margin of the check opposite to or 70 in register with the appropriate designating numeral or character. This notching device, according to the present invention, comprises a notching member 3 which is in the form substantially of a lever having an 75 intermediate portion 4, a notching tongue 5 at one end an operating arm 6 at its opposite end. The notching device is located preferably on a portion of the base plate 1 which extends beyond the lower end of the 80 pad or pack of checks. As shown in the present instance, the extension 1^a of the base plate is for this purpose formed with an opening 7 which may be punched or otherwise suitably formed therein and the edges 85 of the material of the base plate adjacent to this opening are bent rearwardly and in parallelism to form a pair of pivot supporting ears or lugs 8. The intermediate portion 4 of the notching member is mounted in the 90 opening 7 and between the ears or lugs 8 and a pivot pin 9 which extends through the ears and the intermediate portion of the notching member serves to pivotally support the latter in operative position on the base 95 plate. The notching tongue 5 on the notching member is offset relatively to the pivot 9 to an extent sufficient to space it forwardly from the forward side of the base plate extension 1^a when the notching member is 100 swung in one direction, thus providing a space between the notching tongue and the base plate to receive an edge of a detached check, for notching thereof. This notching tongue is preferably of substantially triangular form, as shown, and its apex and its sides are sharpened. The arm 6 on the opposite end of the notching member is offset rearwardly relatively to the notching tongue 5 and it is also offset rearwardly relatively to 105

110

the pivot 9, so that it will be spaced rearwardly from the rear side of the base plate. A suitable spring is preferably provided which acts to swing the arm 6 rearwardly or 5 away from the base plate, thus retracting the notching tongue 5 to permit insertion of the edge of a check. As shown in Figures 1, 2 and 3, a coiled compression spring 10 is shown interposed between the base plate and the arm 10 6 to serve this purpose; and in Figures 4 and 5 a leaf spring 11 is shown attached to the arm 6 and arranged to bear against the rear side of the base plate, to serve the same purpose. In both instances, the spring will act 15 to retract the notching tongue 5 from the forward side of the base plate, so that a check detached from the pad or pack may be readily inserted beneath the notching tongue and when the check has been adjusted so that 20 the notching tongue is opposite to or in register with the appropriate designating numeral or character to be marked, the arm 6 is pressed forwardly by the finger, the notching tongue being thereby moved toward the 25 base plate and caused to grip and firmly clamp the check in proper position. While the check is so held, it is notched by swinging forwardly the edge of the check opposite to the edge engaged by the notching tongue, the 30 sharpened point and side edges of the notching tongue then acting to cleanly notch the edge of the check at the point engaged by the notching tongue. In order to limit the angle through which the notching member swings 35 under the action of the spring 10 or 11, the intermediate portion 4 of the notching member may be formed with a shoulder 12 so positioned as to engage the underside of the base plate adjacent to the forward margin 40 of the opening 7, the size of the opening beneath the notching tongue for the insertion 45 of the check being thus determined by this shoulder.

By constructing the notching member in the form of a lever having relatively offset ends, the forward end of the lever which constitutes the notching tongue may be located at the forward side of the base plate or support and hence the operation of inserting and placing the detached check in proper position relatively to the notching tongue is greatly facilitated, inasmuch as the notching tongue is visible to the operator, and the rear end of the lever may be located behind the base plate or support, out of the way of the pack of checks, and it may be easily engaged and pressed forwardly by the finger of the operator. The intermediate portion of the lever which 50 extends through the base plate provides a convenient means for pivotally mounting the lever, its side adjacent to the base of the notching tongue provides a stop to gage the depth to which the detached check is inserted, and it may also provide a stop to limit 55

the movement of the lever under the action of the spring, thus regulating the space beneath the notching tongue for the insertion of the check.

I claim as my invention:

1. A check notching device comprising a support having an opening therein, and a notching member embodying an intermediate portion pivotally mounted in said opening and having relatively offset ends 75 extending in opposite directions at the respective opposite sides of the support, one of said ends being adapted to clamp a portion of a check against the support and constituting a notching tongue and the other 80 end constituting an operating part.

2. A check notching device comprising a support having an opening therein, and a notching member embodying a lever having an intermediate portion movably extending 85 through said opening and having its ends relatively offset and arranged at the respective sides of the support, one of said ends being shaped to clamp an edge of a check and constituting a notching tongue and the 90 other end constituting an operating arm.

3. A check notching device comprising a support having an opening therein, a co-operative notching member embodying a lever the intermediate portion of which extends movably through said opening, one end of the lever being adapted to bear flatwise against the surface of a check and constituting a notching tongue and being located at one side of the support to clamp the check against it and the other end of the lever being located at the other side of the support and constituting an operating arm, and means acting to move the notching tongue in a direction away from the respective side of the support.

4. A check notching device comprising a support, a notching member embodying a lever formed at one end with a notching tongue arranged at one side of the support and having a substantially flat clamping portion to bear against the face of a check thereon, the lever being formed at the other end with an operating arm arranged at the opposite side of the support, and means 115 acting on said lever to move it in one direction relatively to the support.

5. A device of the character described comprising a base plate having means for holding a pack of checks at the forward side thereof and provided with an opening beyond an edge of said pack, and a check notching member having its intermediate portion pivotally mounted in said opening, one end of said member overlying the forward side of the base plate and constituting a notching tongue and the other end of said member being arranged behind the base plate and constituting an operating lever.

6. A check notching device comprising a 130

support having an opening extending therethrough, and a notching member having an intermediate portion pivotally mounted in said opening, one end of said member overlying one side of the support and constituting a notching tongue, and the other end of said member overlying the opposite end of the support and constituting an operating arm, the intermediate portion of the member providing a stop adjacent to the

notching tongue to gage the depth to which the check to be notched is inserted.

In testimony whereof I have hereunto set my hand in presence of two subscribing witnesses.

PHILIP C. SNOW.
